CIRCUIT BREAKER

Thomas M. Cole, New York, N. Y., assignor to
 Federal Electric Products Company, Newark,
 N. J., a corporation

Application November 15, 1949, Serial No. 127,433

54 Claims. (Cl. 200—116)

1

This invention relates to automatic circuit breakers and more particularly, but without restriction, to circuit breakers of the general type disclosed in United States Patents Nos. 2,174,669 dated October 3, 1939, 2,209,319, 2,209,352 and 2,209,353 each dated July 30, 1940 and Re. 23,188 dated January 10, 1950.

One object of the present invention is the provision of a circuit breaker of the type referred to with improved means for operatively connecting the handle to the movable contact member.

Another object is to provide a construction which enables the elimination of insulation between the movable contact member and the lever which is connected thereto for moving said contact member.

Another object is the provision of a circuit breaker having an arcing chamber of improved construction.

A further object is the provision of an improved terminal arrangement and construction.

The above and other objects, features and advantages of the invention will be fully understood from the following description, considered in connection with the accompanying illustrative drawings.

In the drawings:

Fig. 1 is a side view of a circuit breaker embodying the present invention;

Figs. 2 and 3 are end views as seen from lines 2—2 and 3—3, respectively, of Fig. 1;

Fig. 4 is a side view of the circuit breaker, one part of the casing being removed, the circuit breaker mechanism being open;

Fig. 5 is a view similar to Fig. 4 showing the circuit breaker mechanism closed;

Fig. 6 is a sectional view on the line 6—6 of Fig. 5;

Fig. 7 is a sectional view on the line 7—7 of Fig. 5;

Fig. 8 is a fragmentary sectional view on the line 8—8 of Fig. 5; and

Fig. 9 is a perspective view of the actuating member of the circuit breaker, a portion thereof being cut away for the purpose of illustration.

Referring now to the drawings in detail, the circuit breaker of the present invention comprises a two part insulation housing or casing 10 formed by body part 12 and the cover or closure part 14, each of said parts being formed of insulation material preferably by a molding operation, and being secured in housing-defining relation in any suitable way, for example by bolts 16.

In the illustrated embodiment of the invention, the circuit breaker is of the "plug-in" type for use

2

with a terminal plate assembly such as that described in application, Ser. No. 127,432 filed November 15, 1949, by me and Paul M. Christensen, as joint inventors, and assigned to the assignee of my present application. It will be understood, however, that the present invention is not limited to "plug-in" circuit breakers but is applicable as well to circuit breakers which are not provided with plug-in terminals. The housing is provided, 10 above a re-entrant portion 20, with a chamber 22. A plug-in terminal prong or stab contact 24 is mounted vertically in said chamber, said stab contact being adapted for making contact with said terminal block unit and being provided with 15 the laterally extending portions or arms 26 which are removably positioned in cooperating recesses 27 formed in the walls of said chamber, as illustrated and described in said application. It will be understood that any other suitable type of stab contact may be used in place of the stab contact 24 illustrated in the drawings herein, for example, and not by way of limitation, the other form of stab contact illustrated and described in the above identified copending application.

20 The casing is provided, above the open recess 18 therein, with an arcing chamber 28 in which the stationary contact 30 and the movable contact 32 are disposed for relative movement. It will be noted that said arcing chamber is bounded by the similarly thickened portions 34, 36 and 38 of wall 40 of the body part, and by the portion 42 of said wall, which extends between the portions 36 and 38, and which is thickened to a lesser extent than said other portions. It will be noted 25 also that portion 38 is provided with a shoulder 44 where it extends above portion 42 and that portion 36 is provided with an angular step 46 where it extends above portion 42. The cover part 14 is provided on its inner surface with a thickened portion 48 having a form complementary to portion 42 of wall 40. When the body and cover parts are in housing-defining relation, the ends 50 and 52 of said portion 48 abut the shoulder 44 and the step 46, respectively, as 30 illustrated in Fig. 8, and said portion together with portion 42, the confronting surfaces of which are spaced as at 55, form a bounding wall for the arcing chamber in opposition to the wall thereof formed by the thickened portion 34. Therefore, 35 it will be noted that with the body and cover parts secured together, the casing is provided with an arcing chamber which is closed on all sides thereof except at its opening externally of the casing whereby arcs which may be formed 40 upon the disengagement of contacts 30 and 32

are to a very considerable extent prevented from entering that portion of the casing in which the circuit breaker mechanism is contained.

A chamber 54 for containing the circuit breaker mechanism is formed by the opposing raised edge portions 56 and 58 of wall 40, by the raised portion 60 of said wall, which also bounds chamber 22, by portions 38, 42 and 48 opposing said portion 60, and by wall 40 and cover 14. The edge portion 56 is provided with an opening 62 therein through which a handle 64 projects for manual operation of the circuit breaker mechanism. The handle is formed of insulation material and is provided with the laterally extending circular pivot portions 65, 65, which are positioned in the bearing recesses 67, 67, respectively, formed in each of the casing parts.

Referring now to the circuit breaker mechanism disposed in chamber 54, said mechanism includes a manually operable member, here shown as the above-mentioned pivoted handle 64. A uni-planar movable contact member 66, formed in one piece, is provided with a portion 68 having a high resistance to the flow of current therethrough, and a portion 70 having a low resistance to current flow therethrough. Specifically, portion 68 is formed of a high resistance metal, such as, for example and without limitation, Nichrome or other suitable metal, and portion 70 is formed of a low resistance metal, such as, for example, and without limitation, bronze, or other suitable metal, and said two portions are secured to each other in edge to edge relation in any suitable way, for example by welding or brazing. Contact member 66 may be formed of powdered metal by a molding operation, with parts 68 and 70 of metal powder of high and low resistance, respectively. Said movable contact member is mounted in the chamber 54 for pivotal movement by pivot pin 72, the opposite ends of which are received in the aligned bearing projections 74 on the inner surfaces of each of the casing parts. The low resistance portion 70 is provided with the contact 32 which is engageable with and disengageable from the companion stationary contact 30 carried by the terminal member 76, which will hereinafter be more particularly described. It will be understood that in respect to other features of the invention, the latter are not limited to a movable contact member 66 formed of different metals but apply as well to a circuit breaker in which the movable contact member is formed of one metal, as in the above mentioned patents, for example. The aforementioned complementary casing portions 42 and 48 form a guideway for the movable contact member, the space 55 between the confronting surfaces thereof defining a guide slot through which an end portion 78 of the movable contact member projects with slight clearance, as illustrated in Figs. 7 and 8. It will be noted from Fig. 4 that the end portion 78 of the movable contact member abuts step 46 in the disengaged condition of the companion contacts, said step serving to limit the movement of the movable contact member in its circuit-open position.

At its end portion 78, the movable contact member is provided with an integral depending portion 80 which extends through a slot 82 at one end of a thermal-current responsive member 84 which, as here shown, consists of a thermostatic bi-metallic flexible strip which is welded or otherwise secured at said end thereof to a side edge of movable contact member 66. The free

end of bi-metallic strip 84 is arranged to releasably engage the latch element 86 at one end of an actuating member or lever 88 pivotally mounted on the end of movable contact member 66 opposite the end which carries the contact 32.

As here shown, the lever 88 is formed in one piece of sheet metal and comprises the laterally spaced opposing walls 90, 90 open between the marginal edges 92, 92 thereof, and partially closed between the opposite marginal edges 94, 94 thereof, by the integral wall 96 which is provided with the aforementioned latch element 86, depending below said opposing walls, and with the longitudinal reinforcing bead 98 offset laterally outwardly thereof. The walls 90, 90 are provided with the confronting punched-in, cylindrical projections 100, 100, respectively, which are mounted for pivotal movement in a bearing aperture 102 provided in the movable contact member 66 at the aforementioned opposite end thereof. An insulation bushing 103 is provided in bearing aperture 102 to insulate lever 88 from contact member 66, although this is not strictly necessary when said contact member has the high resistance portion 68 or when lever 88 is made of a metal having a substantially higher resistance than that of the movable contact member. It will be noted from Figs. 6 and 7, that when the lever 88 is mounted on the movable contact member 66, the walls 90 straddle said movable member. At their free ends, each wall 90 is provided with an aperture 104. One end 106 of a resilient link 108 extends with slight clearance through the aligned apertures 104 (Fig. 6) and the other end of said link is pivotally engaged with the adjacent end of handle 64. A coil compression spring 110 is operatively interposed between the movable contact member 66 and handle 64 for biasing the movable contact member to its open position. One end of said spring engages a lug 112 carried by handle 64 and the other end of said spring engages a lug 114 integral with the movable contact member 66. The mechanism constituted by handle 64, movable contact member 66, thermal strip 84, lever 88 and link 108 is similar to and operates substantially in the same way as corresponding mechanism in the above identified United States Patent No. 2,459,427.

It will be observed that the U-shaped construction of lever 88 obviates the need for providing the movable contact member with the laterally offset parts provided in the movable contact member of said Patent No. 2,459,427, and simplifies the pivotal connection of said lever to said movable contact member and the insulation between said two members when insulation is required. Also, the surface of element 86 which engages the free end of strip 84 is free of burrs and is smooth so as not to impede the release of strip 84 when the latter is deflected upon overload.

Also as here shown, the movable contact member 66 is provided with a generally circular, peripherally interrupted, tapered aperture 116 and a tapered pin 118 for calibrating the circuit breaker. Said aperture is formed in the marginal edge of said movable contact member at the junction of the narrowed portion 120 thereof, on which lever 88 is pivotally mounted, and the wider body portion 122 thereof. It will be understood that as pin 118 is forced into aperture 116, the portion of the movable contact member at the right of pin 118 (Figs. 4 and 5) is bent upwardly in its own plane to decrease the amount

of overlap of the detent element 86 at the edge 124 of strip 84 so that less deflection of said strip is required to trip the breaker.

It will be understood that member 84 operates to latch the manually operable actuating mechanism 88 to the movable contact member 66 and to unlatch the actuating mechanism from the movable contact member, the unlatching taking place upon deflection of member 84 causing the disengagement of end 124 thereof from the edge of latch element 86 of lever 88 upon the occurrence of an overload or under other abnormal predetermined current conditions in the circuit controlled by the circuit breaker. When member 84 is deflected from engagement with lever 88, spring 118 is effective to move contact member 66 to its open position, i. e., from the position illustrated in Fig. 5 to the position illustrated in Fig. 4. As heretofore mentioned, the step 46 constitutes a stop for the member 66 to limit the opening movement of the latter.

The thermal element 84 is connected in series with movable contact member 66 and the circuit which is to be controlled by the circuit breaker. For this purpose a flexible metallic conductor or connector 126 is connected to said thermal element, preferably adjacent to the free end 124 thereof, and extends from chamber 54, through an opening 61 in wall portion 60, into chamber 22 for connection to the stab contact 24 which makes contact with a power line in the terminal panel assembly of the co-pending application described above. Although member 84 is in electrical contact with the movable contact member 66 through lever 88, in the closed condition of the circuit breaker, it will be understood that due to the high resistance characteristic of the material forming portion 68 of the movable contact member, the current will not by-pass member 84 by flowing through the lever but substantially all the current will flow through member 84 into portion 78 of the movable contact member and through the engaged contacts 30 and 32. To achieve the same result, it will be understood that the movable contact member need not be formed of portions having high and low resistance characteristics, but that the actuating member 88 may be formed of a high resistance material, such as Nichrome, or other suitable material, to prevent the flow of current therethrough and into the movable contact member.

Load terminal 76, which carries the stationary contact 38, is positioned in an open recessed portion 128 formed in the casing. Said terminal comprises an integral conducting strip 130 which is shaped to form the vertically disposed opposing walls 132 and 134, and the horizontally disposed opposing walls 136 and 138 of the terminal, when the casing is mounted in the position illustrated in Figs. 1 through 5. One end portion 140 of said strip extends inwardly beyond wall 134 and carries the stationary contact 38. The inner end of part 140 abuts the shoulder portion 142 defined by wall portion 38 of the casing body to position contact 38 in relation to contact 32. The lower end of wall 134 is of reduced width and passes through an opening in wall 138 and is bent under the latter as indicated at 148. Said end portion 140 is provided with the laterally extending projections 144 which extend into aligned recesses 146 in the confronting surfaces of both casing parts. Portion 148 abuts a stop 150 formed in portion 34 of body part 12 and overlying an extending portion 152 thereof. It will be noted that when the cover member 14 is

secured to the body part 12, the terminal 76 cannot be removed from the casing, movement in a horizontal plane being prevented by shoulder 142 and stop 150, and movement in a vertical plane being prevented by the arms 144 positioned in the recesses 146, and the underlying projection 152 and the overlying portion 154 of wall portion 38 which abuts the upper surface of strip portion 148. A terminal screw 156 is engaged in a threaded aperture in wall 136 and aperture 158 is formed in wall 132 for the insertion of a lead wire between said terminal screw and the upper surface of wall 138.

As illustrated, the thermal current-responsive member 84 is preferably operable not only in response to the heating effect of the current passing therethrough, but is also operable under the control of electro-magnetic means for effecting disengagement of the companion relatively movable contacts 30 and 32, and the arrangement is preferably such that, as here shown, the electro-magnetic means is energized by the current which passes through the said thermal current-responsive member. For this purpose an electro-magnetic member 160 is fixedly secured, preferably by welding, or in other suitable manner, on member 84 near the free end thereof and a companion rigid armature 162 is disposed in spaced confronting relation to electro-magnetic member 160. As shown in Fig. 6, magnetic member 160 straddles member 84 by which it is carried. Said member 160 is formed in one piece of soft sheet steel or other suitable sheet metal and is provided with an end wall, opposed side walls, and with out-turned end portions 164 which are arranged in surface-confronting relation to the adjacent surface of armature 162. As shown in Fig. 8, armature 162 is provided with a slotted portion 166, opposite the free end thereof, which is aligned with slot 82 in member 84. The armature is secured to the fixed end of member 84, preferably by welding, and side portions 168 thereof are bent around the marginal side edges of member 84, the depending portion 80 of movable member 66 extending through said aligned slots and being riveted to the outer surface of the armature. At its free end, the armature is provided with the out-turned portions 170 which are disposed in spaced confronting relation with the portions 164 of the electro-magnetic member 160. The electro-magnetic member 160 and the armature 162 operate substantially in the same way as corresponding mechanism in said United States Patent No. 2,459,427.

The subject matter of the present application, which is concerned with calibration of the circuit breaker, is related to my copending application Serial No. 213,591, filed March 2, 1951, and assigned to the assignee hereof.

While I have shown and described the preferred embodiment of my invention, it will be understood that the latter may be embodied otherwise than as herein specifically illustrated or described and that in the illustrated embodiment certain changes in the details of construction and in the arrangement of parts may be made without departing from the underlying idea or principles of the invention within the scope of the appended claims.

Having thus described my invention, what I claim and desire to secure by Letters Patent is:

1. In an automatic circuit breaker having a stationary contact, a movable contact engageable and disengageable therewith, actuating means for operatively effecting the engagement

thereof and a thermally-responsive bi-metallic strip for effecting the disengagement thereof; a uni-planar movable contact member on which said movable contact and said strip are bodily carried, said actuating means being pivotally carried thereby and being in normal engagement with said strip to prevent relative pivotal movement.

2. In an automatic circuit breaker having a stationary contact, a movable contact engageable and disengageable therewith, actuating means for operatively effecting the engagement thereof and a thermally-responsive bi-metallic strip for effecting the disengagement thereof; the combination with said actuating means of a uni-planar movable contact member on which said movable contact and said strip are bodily carried, said actuating means comprising a member straddling said movable contact member, and pivotally carried thereby, said straddling member being in normal engagement with said strip to prevent relative pivotal movement.

3. In an automatic circuit breaker having a stationary contact, a movable contact engageable and disengageable therewith, actuating means for operatively effecting the engagement thereof and a thermally-responsive bi-metallic strip for effecting the disengagement thereof; the combination with said actuating means of a movable contact member on which said movable contact and said strip are bodily carried, said actuating means being pivotally carried thereby and being in normal engagement with said strip to prevent relative pivotal movement, said actuating means comprising a lever member in direct electrical contact with both said strip and said movable contact member, one of said members being of such character as to cause substantially all of the current in the circuit to pass through said strip.

4. In an automatic circuit breaker having a stationary contact, a movable contact engageable and disengageable therewith, actuating means for operatively effecting the engagement thereof, and a thermally-responsive bi-metallic strip for effecting the disengagement thereof; the combination with said actuating means of a movable contact member on which said movable contact and said strip are bodily carried, said actuating means being pivotally carried thereby and being in normal engagement with said strip to prevent relative pivotal movement between said movable contact member and said actuating means, said actuating means comprising a lever member in direct contact with both said strip and said movable contact member, and means integral with one of said members for directing substantially all of the current in the circuit through said strip, said last mentioned means comprising a portion of said movable contact member having a low resistance to current flow and a portion thereof having a high resistance to current flow, said low resistance portion being in the path of current flow between said strip and said movable contact and said high resistance portion being in the path of current flow between said lever member and said movable contact.

5. In an automatic circuit breaker having a stationary contact, a movable contact engageable and disengageable therewith, actuating means for operatively effecting the engagement thereof and a thermally-responsive bi-metallic strip for effecting the disengagement thereof; the combination with said actuating means of a movable contact member on which said movable contact and

said strip are bodily carried, said actuating means being pivotally carried thereby and being in normal engagement with said strip to prevent relative pivotal movement, said actuating means comprising a member straddling said movable contact member and in direct contact with both said strip and said movable contact member, said straddling member being formed of a material having a high resistance to current flow whereby substantially none of the current in the circuit will flow therethrough.

6. In an automatic circuit breaker having a stationary contact, a movable contact engageable and disengageable therewith, actuating means for operatively effecting the engagement thereof and a thermally-responsive bi-metallic strip for effecting the disengagement thereof; the combination with said actuating means of a movable contact member on which said movable contact and said strip are bodily carried, said actuating means being pivotally carried thereby and being in normal engagement with said strip to prevent relative pivotal movement, said actuating means comprising a lever member in direct contact with both said strip and said movable contact member, said lever member being formed of a material having a high resistance to current flow whereby substantially none of the current in the circuit will flow therethrough.

7. In an automatic circuit breaker, a stationary contact, a movable contact member provided with a contact engageable with and disengageable from said stationary contact, manually operable actuating means, and a current-responsive member for effecting disengagement of said contacts in response to predetermined current in the circuit, said current-responsive member being movable relatively to said movable contact member for latching the latter to and unlatching it from said actuating means, said actuating means being a lever provided with portions straddling said movable contact member and with portions in pivotal engagement therewith and having a part releasably engageable with said current-responsive member.

8. In an automatic circuit breaker, a stationary contact, a movable contact member provided with a contact engageable with and disengageable from said stationary contact, manually operable actuating means, and a current-responsive member for effecting disengagement of said contacts in response to predetermined current in the circuit, said current-responsive member being movable relatively to said movable contact member for latching the latter to and unlatching it from said actuating means, said actuating means being a lever provided with portions straddling said movable contact member and with portions in pivotal engagement therewith, said lever having a latch element integral with said straddling portions in position therebetween and in latching engagement with said current-responsive member.

9. In an automatic circuit breaker having a stationary contact, a movable contact member provided with a contact engageable with and disengageable from said stationary contact, manually operable actuating means and a thermally-responsive bi-metallic strip for effecting disengagement of said contacts in response to predetermined current in the circuit, said strip being carried by and bodily movable with said movable contact member and also movable relatively thereto for latching the latter to and unlatching it from said actuating means; a depending por-

tion carried by said movable contact member and extending through said strip, an armature having a surface portion in abutment with a surface of said strip and provided with confronting portions in engagement with the opposite surface of said strip, said depending portion extending through said armature and being secured to an opposite surface portion thereof, and a companion magnetic member carried by said strip and movable in relation to said armature in response to predetermined current in the circuit whereby to move said strip to unlatch said movable contact member from said actuating means independently of the response of said strip itself to the current.

10. In an automatic circuit breaker having a stationary contact, a movable contact member provided with a contact engageable with and disengageable from said stationary contact, manually operable actuating means, and a thermally-responsive bi-metallic strip for effecting disengagement of said contacts in response to predetermined current in the circuit, said strip being carried by and bodily movable with said movable contact member and also movable relatively thereto for latching the latter to and unlatching it from said actuating means; a depending portion carried by said movable contact member and extending through said strip, an armature having a surface portion in abutment with a surface of said strip and provided with confronting portions in engagement with the opposite surface of said strip, said depending portion extending through said armature and being secured to an opposite surface portion thereof, and a companion magnetic member carried by said strip and movable in relation to said armature in response to predetermined current in the circuit whereby to move said strip to unlatch said movable contact member from said actuating means independently of the response of said strip itself to the current, said magnetic member being secured to said strip against movement relative thereto.

11. In an automatic circuit breaker having a stationary contact, a movable contact member provided with a contact engageable with and disengageable from said stationary contact, manually operable actuating means and a thermally-responsive bi-metallic element for effecting disengagement of said contacts in response to predetermined current in the circuit, said element being carried by and bodily movable with said movable contact member and also movable relatively thereto for latching said element to and unlatching it from said actuating means; means for calibrating the movement of said element relative to said movable contact member comprising a marginal edge portion of said movable contact member in which is defined a peripherally interrupted aperture, and a tapered member engaged in said aperture for displacing said marginal edge portion of said movable contact member so as to change the relationship of said bi-metallic element with respect to the main body of said movable contact member.

12. In an automatic circuit breaker having a stationary contact, a movable contact member provided with a contact engageable with and disengageable from said stationary contact, manually operable actuating means and a thermally-responsive bi-metallic element for effecting disengagement of said contacts in response to predetermined current in the circuit, said element being carried by and bodily movable with said movable contact member and also movable rela-

tively thereto for latching said element to and unlatching it from said actuating means; means for calibrating the movement of said element relative to said movable contact member comprising a marginal edge portion of said movable contact member in which is defined a peripherally interrupted aperture, and a tapered member engaged in said aperture for displacing said marginal edge portion of said movable contact member so as to change the relationship of said bi-metallic element with respect to the main body of said movable contact member, said marginal edge portion being at the juncture of a narrower portion of said movable contact member and the main body thereof, said actuating means being mounted on said narrower portion and said narrower portion being displaceable relative to said main body so as to change the relationship of said bi-metallic element with respect to said actuating means.

20 13. In an automatic circuit breaker, a casing provided with an arcing chamber and a chamber in which the circuit breaker mechanism is disposed, said chambers being separated by a wall formed by complementary portions provided on 25 confronting surfaces of said casing, one of said portions having raised end parts and the other of said portions being removably engageable between said end parts, in abutment therewith, the confronting surfaces of said portions defining a 30 guideway, a stationary contact disposed in said arcing chamber, and a movable contact member mounted in the other chamber and having a portion disposed in said guideway and extending into said arcing chamber, said latter portion being provided with a movable contact engageable with and 35 disengageable from said stationary contact, said wall encompassing said latter portion for confining arcing within said arcing chamber.

14. In an automatic circuit breaker, a casing 40 provided with an arcing chamber and a chamber in which the circuit breaker mechanism is disposed, said chambers being separated by a wall formed by complementary portions provided on 45 confronting surfaces of said casing, one of said portions having raised end parts and the other of said portions being removably engageable between said end parts, in abutment therewith, the confronting surfaces of said portions defining a guideway, a stationary contact disposed in said arcing chamber, and a movable contact member 50 mounted in the other chamber and having a portion disposed in said guideway and extending into said arcing chamber, said latter portion being provided with a movable contact engageable with and disengageable from said stationary contact, said 55 wall encompassing said latter portion for confining arcing within said arcing chamber, said end parts being shoulders formed in opposing walls of said arcing chamber, the ends of said other casing portion being retained against displacement by said shoulders.

15. In an automatic circuit breaker, a casing 60 having an open recessed portion and an arcing chamber adjacent thereto, said recessed portion and said arcing chamber being separated by an apertured portion of said casing forming a wall of said chamber, and a terminal member disposed in said recessed portion and mounted on said wall, said member having a contact carrying part extending through said aperture and 65 abutting the surface of said wall opposite the surface on which said member is mounted.

16. In an automatic circuit breaker, a casing 70 having an open recessed portion and an arcing chamber adjacent thereto, said recessed portion

and said arcing chamber being separated by an apertured portion of said casing forming a wall of said chamber, and a terminal member disposed in said recessed portion and mounted on said wall, said member having a contact carrying part extending through said aperture and abutting the surface of said wall opposite the surface on which said member is mounted, said wall having a step formed in said last mentioned surface thereof and a shoulder at said first mentioned surface thereof, said contact carrying part abutting said shoulder and said terminal member having a part engaged in said step.

17. In an automatic circuit breaker, a casing having an open recessed portion and an arcing chamber adjacent thereto, said recessed portion and said arcing chamber being separated by an apertured portion of said casing forming a wall of said chamber, and a terminal member disposed in said recessed portion and mounted on said wall, said member having a contact carrying part extending through said aperture and abutting the surface of said wall opposite the surface on which said member is mounted, said wall having a step formed in said last mentioned surface thereof and a shoulder at said first mentioned surface thereof, said contact carrying part abutting said shoulder and said terminal member having a part engaged in said step, said terminal member comprising a continuous strip, said latter part being at one end thereof and said contact carrying part being at the other end thereof.

18. In an automatic circuit breaker, an insulation casing formed of companion complementary parts mutually secured in housing-defining relation, and a stab terminal member contained in said casing and having a portion extending therefrom for effecting contact between said circuit breaker and a companion contact terminal, said casing parts and said stab terminal member being provided with inter-engaging portions for releasably retaining said stab terminal member in operative disposition in said casing.

19. In an automatic circuit breaker, an insulation casing formed of companion complementary parts mutually secured in housing-defining relation, and a stab terminal member contained in said casing and having a portion extending therefrom for effecting contact between said circuit breaker and a companion contact terminal, said casing parts and said stab terminal member being provided with cooperating elements for releasably retaining said stab terminal member in operative disposition in said casing, said cooperating elements comprising laterally extending portions of said stab terminal member and recessed portions in the confronting surfaces of said complementary casing parts, said laterally extending portions being removably engageable in said recessed portions whereby said stab terminal member is supported in said casing parts in axial disposition thereof.

20. In an automatic circuit breaker, an insulation casing having portions defining a chamber in which the circuit breaker mechanism is disposed and a chamber having an opening extending through the surface of said casing, one of said portions being common to said chambers and having an aperture therein, a stab terminal member mounted in said latter chamber and having a portion extending through said opening in the casing surface for effecting contact with a companion contact terminal, and con-

ducting means extending through said aperture, one end of said conducting means being connected to said stab terminal member, the other end thereof being connected to said circuit breaker mechanism.

21. In an automatic circuit breaker, a casing provided with an arcing chamber and a chamber in which the circuit breaker mechanism is disposed, said chambers being separated by a wall formed by complementary portions provided on confronting surfaces of said casing, one of said portions having raised end parts and the other of said portions being removably engageable between said end parts, in abutment therewith, the confronting surfaces of said portions defining a guideway, a stationary contact disposed in said arcing chamber, a uni-planar movable contact member mounted in the other chamber and having a portion disposed in said guideway and extending into said arcing chamber, said latter portion being provided with a movable contact engageable with and disengageable from said stationary contact, said wall encompassing said latter portion for confining arcing within said arcing chamber, actuating means for operatively effecting the engagement of said contacts, and a thermally responsive bi-metallic strip for effecting the disengagement thereof, said strip being bodily carried by said movable contact member, said actuating means being pivotally carried thereby and being in normal engagement with said strip to prevent relative pivotal movement.

22. In an automatic circuit breaker, a casing having an open recessed portion and an arcing chamber adjacent thereto, said recessed portion and said arcing chamber being separated by an apertured portion of said casing forming a wall of said chamber, a terminal member disposed in said recessed portion and mounted on said wall, said member having a contact carrying part extending through said aperture and abutting the surface of said wall opposite the surface on which said member is mounted, a movable contact engageable and disengageable with said terminal contact, actuating means for operatively effecting the engagement thereof, a thermally-responsive bi-metallic strip for effecting the disengagement thereof, and a uni-planar movable contact member on which said movable contact and said strip are bodily carried, said actuating means being pivotally carried thereby and being in normal engagement with said strip to prevent relative pivotal movement.

23. In an automatic circuit breaker, an insulation casing having portions defining a chamber in which the circuit breaker mechanism is disposed and a chamber having an opening extending through the surface of said casing, one of said portions being common to said chambers and having an aperture therein, a stab terminal member mounted in said latter chamber and having a portion extending through said opening in the casing surface for effecting contact with a companion contact terminal, a stationary contact, a movable contact engageable and disengageable therewith, actuating means for operatively effecting the engagement thereof, a thermally-responsive bi-metallic strip for effecting the disengagement thereof, a uni-planar movable contact member on which said movable contact and said strip are bodily carried, said actuating means being pivotally carried thereby and being in normal engagement with said strip to prevent relative pivotal move-

ment, and conducting means extending through said aperture, one end of said conducting means being connected to said stab terminal member, the other end thereof being connected to said strip.

24. In an automatic circuit breaker, a casing provided with an arcing chamber and a chamber in which the circuit breaker mechanism is disposed, said chambers being separated by a wall formed by complementary portions provided on confronting surfaces of said casing, one of said portions having raised end parts and the other of said portions being removably engageable between said end parts, in abutment therewith, the confronting surfaces of said portions defining a guideway, a stationary contact disposed in said arcing chamber, a uni-planar movable contact member mounted in the other chamber and having a portion disposed in said guideway and extending into said arcing chamber, said latter portion being provided with a movable contact engageable with and disengageable from said stationary contact, said wall encompassing said latter portion for confining arcing within said arcing chamber, actuating means for operatively effecting the engagement of said contacts, a thermally responsive bi-metallic strip for effecting the disengagement thereof, said strip being bodily carried by said movable contact member, said actuating means being pivotally carried thereby and being in normal engagement with said strip to prevent relative pivotal movement, said casing having an open recessed portion adjacent said arcing chamber, said recessed portion and said arcing chamber being separated by an apertured portion of said casing forming another wall of said arcing chamber, and a terminal member disposed in said recessed portion and mounted on said latter wall, said terminal member having a part extending through said aperture and abutting the surface of said latter wall opposite the surface on which said member is mounted, said stationary contact being carried by said extending part.

25. In an automatic circuit breaker, a casing provided with an arcing chamber and a chamber in which the circuit breaker mechanism is disposed, said chamber being separated by a wall formed by complementary portions provided on confronting surfaces of said casing, one of said portions having raised end parts and the other of said portions being removably engageable between said end parts, in abutment therewith, the confronting surfaces of said portions defining a guideway, a stationary contact disposed in said arcing chamber, a uni-planar movable contact member mounted in the other chamber and having a portion disposed in said guideway and extending into said arcing chamber, said latter portion being provided with a movable contact engageable with and disengageable from said stationary contact, said wall encompassing said latter portion for confining arcing within said arcing chamber, actuating means for operatively effecting the engagement of said contacts, a thermally responsive bi-metallic strip for effecting the disengagement thereof, said strip being bodily carried by said movable contact member, said actuating means being pivotally carried thereby and being in normal engagement with said strip to prevent relative pivotal movement, said casing having an additional chamber provided with an opening extending through the surface of said casing, said casing having a portion common to said additional chamber and the

chamber containing the circuit breaker mechanism, said common portion having an aperture therein, a stab terminal member mounted in said additional chamber and having a portion extending through said opening in the casing surface for effecting contact with a companion contact terminal, and conducting means extending through said aperture, one end of said conducting means being connected to said stab terminal member, the other end thereof being connected to said strip.

26. In an automatic circuit breaker, an insulation casing having portions defining a chamber in which the circuit breaker mechanism is disposed and a chamber having an opening extending through the surface of said casing, one of said portions being common to said chambers and having an aperture therein, a stab terminal member mounted in said latter chamber and having a portion extending through said opening in the casing surface for effecting contact with a companion contact terminal, a stationary contact, a movable contact engageable and disengageable therewith, actuating means for operatively effecting the engagement thereof, a thermally-responsive bi-metallic strip for effecting the disengagement thereof, a uni-planar movable contact member on which said movable contact and said strip are bodily carried, said actuating means being pivotally carried thereby and being in normal engagement with said strip to prevent relative pivotal movement, conducting means extending through said aperture, one end of said conducting means being connected to said stab terminal member, the other end thereof being connected to said strip, said casing having an open recessed portion and an arcing chamber adjacent thereto, said recessed portion and said arcing chamber being separated by an apertured portion of said casing forming a wall of said arcing chamber, and a terminal member disposed in said recessed portion and mounted on said latter wall, said latter terminal member having a part extending through said latter aperture and abutting the surface of said latter wall opposite the surface in which said latter terminal member is mounted, said stationary contact being carried by said extending part.

27. In an automatic circuit breaker, a casing provided with an arcing chamber and a chamber in which the circuit breaker mechanism is disposed, said chambers being separated by a wall formed by complementary portions provided on confronting surfaces of said casing, one of said portions having raised end parts and the other of said portions being removably engageable between said end parts, in abutment therewith, the confronting surfaces of said portions defining a guideway, a stationary contact disposed in said arcing chamber, a uni-planar movable contact member mounted in the other chamber and having a portion disposed in said guideway and extending into said arcing chamber, said latter portion being provided with a movable contact engageable with and disengageable from said stationary contact, said wall encompassing said latter portion for confining arcing within said arcing chamber, actuating means for operatively effecting the engagement of said contacts, a thermally responsive bi-metallic strip for effecting the disengagement thereof, said strip being bodily carried by said movable contact member, said actuating means being pivotally carried thereby and being in normal engagement with said strip to prevent relative pivotal movement, said cas-

ing having an open recessed portion adjacent said arcing chamber, said recessed portion and said arcing chamber being separated by an apertured portion of said casing forming a wall of said arcing chamber, a terminal member disposed in said recessed portion and mounted on said latter wall, said terminal member having a part extending through said aperture and abutting the surface of said latter wall opposite the surface on which said terminal member is mounted, said stationary contact being carried by said extending part, said casing having an additional chamber provided with an opening extending through the surface of said casing, said casing having a portion common to said additional chamber and the chamber containing the circuit breaker mechanism, said common portion having an aperture therein, a stab terminal member mounted in said additional chamber and having a portion extending through said opening in the casing surface for effecting contact with a companion contact terminal, and conducting means extending through said latter aperture, one end of said conducting means being connected to said stab terminal member, the other end thereof being connected to said strip.

28. In an automatic circuit breaker, a casing provided with an arcing chamber and a chamber in which the circuit breaker mechanism is disposed, said chambers being separated by a wall formed by complementary portions provided on confronting surfaces of said casing, one of said portions having raised end parts and the other of said portions being removably engageable between said end parts, in abutment therewith, the confronting surfaces of said portions defining a guideway, a stationary contact disposed in said arcing chamber, a movable contact member mounted in the other chamber and having a portion disposed in said guideway and extending into said arcing chamber, said latter portion being provided with a movable contact engageable with and disengageable from said stationary contact, said wall encompassing said latter portion for confining arcing within said arcing chamber, said casing having an open recessed portion adjacent said arcing chamber, said recessed portion and said arcing chamber being separated by an apertured portion of said casing forming another wall of said arcing chamber, and a terminal member disposed in said recessed portion and mounted on said latter wall, said terminal member having a part extending through said aperture and abutting the surface of said latter wall opposite the surface on which said member is mounted, said stationary contact being carried by said extending part.

29. In an automatic circuit breaker, a casing provided with an arcing chamber and a chamber in which the circuit breaker mechanism is disposed, said chambers being separated by a wall formed by complementary portions provided on confronting surfaces of said casing, one of said portions having raised end parts and the other of said portions being removably engageable between said end parts, in abutment therewith, the confronting surfaces of said portions defining a guideway, a stationary contact disposed in said arcing chamber, a movable contact member mounted in the other chamber and having a portion disposed in said guideway and extending into said arcing chamber, said latter portion being provided with a movable contact engageable with and disengageable from said stationary contact, said wall encompassing said latter portion for

confining arcing within said arcing chamber, said casing having an additional chamber provided with an opening extending through the surface of said casing, said casing having a portion common to said additional chamber and the chamber containing the circuit breaker mechanism, said common portion having an aperture therein, a stab terminal member mounted in said additional chamber and having a portion extending through said opening in the casing surface for effecting contact with a companion contact terminal, and conducting means extending through said aperture, one end of said conducting means being connected to said stab terminal member, the other end thereof being connected to said circuit breaker mechanism.

30. In an automatic circuit breaker, an insulation casing having portions defining a chamber in which the circuit breaker mechanism is disposed and a chamber having an opening extending through the surface of said casing, one of said portions being common to said chambers and having an aperture therein, a stab terminal member mounted in said latter chamber and having a portion extending through said opening in the casing surface for effecting contact with a companion contact terminal, conducting means extending through said aperture, one end of said conducting means being connected to said stab terminal member, the other end thereof being connected to said circuit breaker mechanism, said casing having an open recessed portion and an arcing chamber adjacent thereto, said recessed portion and said arcing chamber being separated by an apertured portion of said casing forming a wall of said arcing chamber, and a terminal member disposed in said recessed portion and mounted on said wall, said latter terminal member having a contact carrying part extending through said aperture and abutting the surface of said wall opposite the surface on which said latter terminal member is mounted, said circuit breaker mechanism being engageable with and disengageable from said contact.

31. In an automatic circuit breaker, a casing provided with an arcing chamber and a chamber in which the circuit breaker mechanism is disposed, said chambers being separated by a wall formed by complementary portions provided on confronting surfaces of said casing, one of said portions having raised end parts and the other of said portions being removably engageable between said end parts, in abutment therewith, the confronting surfaces of said portions defining a guideway, a stationary contact disposed in said arcing chamber, a movable contact member mounted in the other chamber and having a portion disposed in said guideway and extending into said arcing chamber, said latter portion being provided with a movable contact engageable with and disengageable from said stationary contact, said wall encompassing said latter portion for confining arcing within said arcing chamber, said casing having an open recessed portion adjacent said arcing chamber, said recessed portion and said arcing chamber being separated by an apertured portion of said casing forming another wall of said arcing chamber, a terminal member disposed in said recessed portion and mounted on said latter wall, said terminal member having a part extending through said aperture and abutting the surface of said latter wall opposite the surface on which said terminal member is mounted, said stationary contact being carried by said extending part, said casing having an

additional chamber provided with an opening extending through the surface of said casing, said casing having a portion common to said additional chamber and the chamber containing the circuit breaker mechanism, said common portion having an aperture therein, a stab terminal member mounted in said additional chamber and having a portion extending through said opening in the casing surface for effecting contact with a companion contact terminal, and conducting means extending through said latter aperture, one end of said conducting means being connected to said stab terminal member, the other end thereof being connected to said circuit breaker mechanism.

32. In an automatic circuit breaker having a stationary contact, a movable contact member mounted for pivotal movement and provided with a contact engageable with and disengageable from said stationary contact; manually operable means for actuating said movable contact member comprising a lever pivotally mounted on said movable contact member and current responsive means releasably connecting said lever operatively to said movable contact member, said lever being formed in one piece and having laterally spaced parts disposed at opposite sides of said movable contact member and an intermediate part connecting said spaced parts and having a surface portion providing a latch releasably engaged by said current responsive means to provide said releasable operative connection of said lever to said movable contact member.

33. In an automatic circuit breaker having a stationary contact, a movable contact member mounted for pivotal movement and provided with a contact engageable with and disengageable from said stationary contact; manually operable means for actuating said movable contact member comprising a lever pivotally mounted on said movable contact member and current responsive means releasably connecting said lever operatively to said movable contact member, said lever having laterally spaced parts disposed at opposite sides of said movable contact member and an intermediate part connecting said spaced parts and having a surface portion providing a latch releasably engaged by said current responsive means to provide said releasable operative connection of said lever to said movable contact member.

34. In an automatic circuit breaker having a stationary contact, a movable contact member mounted for pivotal movement and provided with a contact engageable with and disengageable from said stationary contact; manually operable means for actuating said movable contact member comprising a lever pivotally mounted on said movable contact member and current responsive means releasably connecting said lever operatively to said movable contact member, said lever being formed of sheet metal and having a laterally extending surface part disposed transversely of said movable contact member, said surface part being adjacent a free end of said lever and providing a latching surface releasably engaged by said current responsive means to provide said releasable operative connection of said lever to said movable contact member.

35. In an automatic circuit breaker having a stationary contact, a movable contact member mounted for pivotal movement and provided with a contact engageable with and disengageable from said stationary contact; manually operable means for actuating said movable contact

member comprising a lever pivotally mounted on said movable contact member and current responsive means releasably connecting said lever operatively to said movable contact member, said lever being formed of sheet metal and having a laterally extending surface part disposed transversely of said movable contact member, said surface part being adjacent a free end of said lever and providing a latching surface releasably engaged by said current responsive means to provide said releasable operative connection of said lever to said movable contact member, said current responsive means comprising a thermoelectric strip having a free end abutting said latching surface in said releasable engagement of said current responsive means with said lever.

36. In an automatic circuit breaker having a stationary contact, a movable contact member mounted for pivotal movement and provided with a contact engageable with and disengageable from said stationary contact; manually operable means for actuating said movable contact member comprising a lever pivotally mounted on said movable contact member and current responsive means releasably connecting said lever operatively to said movable contact member, said lever being formed of sheet metal and having a laterally extending surface part disposed transversely of said movable contact member, said surface part being adjacent a free end of said lever and providing a latching surface releasably engaged by said current responsive means to provide said releasable operative connection of said lever to said movable contact member, said current responsive means comprising a thermoelectric strip carried by said movable contact member and having a free end abutting said latching surface in said releasable engagement of said current responsive means with said lever.

37. In an automatic circuit breaker having a stationary contact, a movable contact member mounted for pivotal movement and provided with a contact engageable with and disengageable from said stationary contact; manually operable means for actuating said movable contact member comprising a lever pivotally mounted on said movable contact member and current responsive means releasably connecting said lever operatively to said movable contact member, said lever having laterally spaced parts disposed at opposite sides of said movable contact member and an intermediate part connecting said spaced parts and having a surface portion providing a latch releasably engaged by said current responsive means to provide said releasable operative connection of said lever to said movable contact member, said current responsive means comprising a thermoelectric strip having a free end abutting said latching surface in said releasable engagement of said current responsive means with said lever.

38. In an automatic circuit breaker having a stationary contact, a movable contact member mounted for pivotal movement and provided with a contact engageable with and disengageable from said stationary contact; manually operable means for actuating said movable contact member comprising a lever pivotally mounted on said movable contact member and current responsive means releasably connecting said lever operatively to said movable contact member, said lever being formed in one piece and having laterally spaced parts disposed at opposite sides of said movable contact member and an intermediate part connecting said spaced parts and having a surface portion providing a latch releasably engaged by said current responsive means to provide said releasable operative connection of said lever to said movable contact member.

a surface portion providing a latch releasably engaged by said current responsive means to provide said releasable operative connection of said lever to said movable contact member, said current responsive means comprising a thermostatic strip having a free end abutting said latching surface in said releasable engagement of said current responsive means with said lever.

39. In an automatic circuit breaker having a stationary contact, a movable contact member mounted for pivotal movement and provided with a contact engageable with and disengageable from said stationary contact; manually operable means for actuating said movable contact member comprising a lever pivotally mounted on said movable contact member and current responsive means releasably connecting said lever operatively to said movable contact member, said lever being formed in one piece of sheet metal and having laterally spaced parts disposed at opposite sides of said movable contact member and an intermediate part connecting said spaced parts and having a surface portion providing a latch releasably engaged by said current responsive means to provide said releasable operative connection of said lever to said movable contact member.

40. In an automatic circuit breaker having a stationary contact, a movable contact member mounted for pivotal movement and provided with a contact engageable with and disengageable from said stationary contact; manually operable means for actuating said movable contact member comprising a lever pivotally mounted on said movable contact member and current responsive means releasably connecting said lever operatively to said movable contact member, said lever being formed of sheet metal and having laterally spaced parts disposed at opposite sides of said movable contact member and an intermediate part connecting said spaced parts and having a surface portion providing a latch releasably engaged by said current responsive means to provide said releasable operative connection of said lever to said movable contact member, said current responsive means comprising a thermostatic strip carried by said movable contact member and having a free end abutting said latching surface in said releasable engagement of said current responsive means with said lever.

41. In an automatic circuit breaker having a stationary contact, a movable contact member mounted for pivotal movement and provided with a contact engageable with and disengageable from said stationary contact; manually operable means for actuating said movable contact member comprising a lever pivotally mounted on said movable contact member and current responsive means releasably connecting said lever operatively to said movable contact member, said lever being formed of sheet metal and having spaced sides provided with integral pivot elements engaging said movable contact member for said pivotal connection of said lever to said movable contact member, said lever having an integral part between said sides disposed transversely of said movable contact member, said surface part being adjacent a free end of said lever and providing a latching surface releasably engaged by said current responsive means to provide said releasable operative connection of said lever to said movable contact member.

42. In an automatic circuit breaker having a stationary contact, a movable contact member mounted for pivotal movement and provided with a contact engageable with and disengageable

from said stationary contact; manually operable means for actuating said movable contact member comprising a lever pivotally mounted on said movable contact member and current responsive means releasably connecting said lever operatively to said movable contact member, said lever being formed of sheet metal and having spaced sides provided with integral pivot elements engaging said movable contact member for said pivotal connection of said lever to said movable contact member, said lever having an integral part between said sides disposed transversely of said movable contact member, said surface part being adjacent a free end of said lever and providing a latching surface releasably engaged by said current responsive means to provide said releasable operative connection of said lever to said movable contact member having a free end abutting said latching surface in said releasable engagement of said current responsive means with said lever.

43. In an automatic circuit breaker having a movable contact member, an actuating member carried by said movable contact member and a flexible control device for operatively connecting said actuating member releasably to said movable contact member for operating the latter except when said control device is disconnected from said actuating member upon overload, a depending portion carried by said movable contact member and extending through said control device, and a substantially rigid armature having a surface portion in abutment with said control device, said depending portion extending through said armature and being secured to an opposite surface portion thereof.

44. In an automatic circuit breaker having a movable contact member; an actuating member carried by said movable contact member, and a control device for operatively connecting said actuating member releasably to said movable contact member for operating the latter except when said control device is disconnected from said actuating member upon overload, said control device being fixed in relation to said movable contact member, and said actuating member being adjustable in relation to said control device to calibrate the circuit breaker for automatic opening thereof upon overload.

45. In an automatic circuit breaker having a movable contact member; an actuating member carried by said movable contact member, and a control device for operatively connecting said actuating member releasably to said movable contact member for operating the latter except when said control device is disconnected from said actuating member upon overload, said control device being fixed in relation to said movable contact member, and said actuating member being adjustable in relation to said control device to calibrate the circuit breaker for automatic opening thereof upon overload, said movable contact member having a bendable part and said actuating member being secured to said bendable part.

46. In an automatic circuit breaker having a movable contact member; an actuating member carried by said movable contact member, and a control device for operatively connecting said actuating member releasably to said movable contact member for operating the latter except when said control device is disconnected from said actuating member upon overload, said control device being fixed in relation to said movable contact member, and said actuating member being adjustable in relation to said control device to calibrate the circuit breaker for automatic opening thereof upon overload, said movable contact

member having a bendable part and said actuating member being secured to said bendable part, said control device being secured to said movable contact member at a point thereof which is spaced from said bendable part.

47. In an automatic circuit breaker having a movable contact member; an actuating member carried by said movable contact member, and a control device for operatively connecting said actuating member releasably to said movable contact member for operating the latter except when said control device is disconnected from said actuating member upon overload, said control device being fixed in relation to said movable contact member, and said actuating member being adjustable in relation to said control device to calibrate the circuit breaker for automatic opening thereof upon overload, said movable contact member having a bendable part and said actuating member being secured to said bendable part, 20 said bendable part having an aperture defined in an edge thereof, and a tapered member pressed into said aperture for bending said part.

48. In an automatic circuit breaker having a movable contact member; an actuating member carried by said movable contact member, and a control device for operatively connecting said actuating member releasably to said movable contact member for operating the latter except when said control device is disconnected from said actuating member upon overload, said control device being fixed in relation to said movable contact member, and said actuating member being adjustable in relation to said control device to calibrate the circuit breaker for automatic opening thereof upon overload, said control device being a bimetallic strip having a free end engageable by said actuating member, and the latter having an end portion which is adjusted in relation to said free end of the bimetallic member by said adjustment of the actuating member.

49. In an automatic circuit breaker, an insulation casing formed of companion complementary parts mutually secured in housing-defining relation, and a stab terminal member contained in said casing and having a portion extending therefrom for effecting contact between said circuit breaker and a companion contact terminal, said casing parts and said stab terminal member being provided with inter-engaging portions for releasably retaining said stab terminal member in operative disposition in said casing, said interengaging portions comprising integral parts of said stab terminal member and integral portions of said casing parts adapted to receive said integral stab parts, respectively.

50. In an automatic circuit breaker, an insulation casing formed of companion complementary parts mutually secured in housing-defining relation, and a prong terminal member carried by said casing, said prong member having an end portion extending from said casing and a portion dis-

posed therein, said latter portion being provided with integral parts, and said casing parts having formations engageable with said integral parts for fixing said prong in operative disposition therein.

51. In an automatic circuit breaker, an insulation casing formed of companion complementary parts mutually secured in housing-defining relation, and a prong terminal member carried by said casing, said prong member having an end portion extending from said casing and a portion disposed therein, said latter portion being provided with integral parts, and said casing parts having formations engageable with said integral parts for fixing said prong in operative disposition therein, said integral parts extending laterally from said prong member and said casing formations being in confronting disposition for receiving said integral parts, respectively.

52. In an automatic circuit breaker, an insulation casing provided with a longitudinally extending prong terminal member projecting therefrom, and cooperating means provided on said member and on said casing for securely retaining said member in longitudinal disposition thereof in said casing.

53. In an automatic circuit breaker, an insulation casing provided with a longitudinally extending prong terminal member projecting therefrom, and cooperating means provided on said member and on said casing for securely retaining said member in longitudinal disposition thereof in said casing, said means provided on said prong member being portions thereof which extend transversely of said casing.

54. In an automatic circuit breaker, an insulation casing provided with a longitudinally extending prong terminal member projecting therefrom, and cooperating means provided on said member and on said casing for securely retaining said member in longitudinal disposition thereof in said casing, said means provided on said prong member being portions thereof which extend transversely of said casing, and said means provided on said casing being confronting formations defined therein for receiving said transversely extending portions.

THOMAS M. COLE.
